UNITED STATES PATENT OFFICE

CASPAR E. HOFBAUER, OF NEW YORK, N. Y., ASSIGNOR TO PARAMOUNT CARBURETOR CORPORATION, OF NEW YORK, N. Y., A CORPORATION OF NEW YORK

CARBURETING SYSTEM

Application filed July 25, 1929. Serial No. 380,857.

My present invention relates generally to a fuel feeding system for gasoline engines of automobiles and the like.

Systems for feeding fuel to the nozzle of an automobile present the source of supply in the form of either a negative fuel head or a positive fuel head. The suction feed from a lower level is an example of the former. Gravity feed from the main tank at a higher lever or from the vacuum tank of a fuel feeding system or fuel pumps are examples of positive heads.

One of the objects of my invention is the provision of an arrangement which may take the form of an attachment to any of the fuel feeding systems now in use which will eliminate the head and any variations thereof as a varying factor in the control of fuel feeding systems, regardless of whether the head is a negative or a positive one.

While I have illustrated my invention as employed in connection with a fuel feed system in which the fuel is lifted by engine suction from a lower level, it will now be understood and will later be pointed out that my invention is equally applicable regardless of the character of the fuel head. For example, it can be employed between the vacuum tank and the nozzle in a suction feed or between the gravity tank and the nozzle in a gravity feed.

In accordance with the disclosure herein made, my invention takes the form of a valve with associated parts open and responsive to the action of the suction beyond the nozzle and also open to the fuel head whether negative or positive and so constructed that the fuel head is resolved thereby into two components acting upon the valve in opposite directions and to the same degree to thereby totally eliminate the fuel head as a factor in controlling or in any way affecting the operation of the valve.

Another object of the invention is the provision of an arrangement that may take the

form of an attachment to any present existing fuel feeding system.

For the attainment of the foregoing objects and such other objects as may hereinafter appear or be pointed out, I have illustrated one embodiment of my invention in the accompanying drawing in which—

The figure is a view partly in section and partly in elevation of a system employing my invention.

The fuel tank 10 is illustrated as at a level below the nozzle 11 of the carburetor and the fuel is lifted from this lower level to the nozzle by engine suction.

While the particular character of carburetor is not part of the present invention, I will describe briefly the type of carburetor which I have illustrated in the drawing.

The fuel drawn through the nozzle 11 passes through the annular space 20 and through the passageway 21, centrally of the venturi 22, which is open to the atmosphere at 23. The mixture is then discharged into the main casing by means of the annular opening 24 and then through the fitting 25 and also through the bent tube 26, discharging centrally of the fitting 24.

30 is a primary air valve automatically controlled by suction conditions thereabove to give the required mixture. The arrangement of the contours of the valve 30 and of the valve seat 31 and of the wall 32 adjacent the valve is an important feature of the carburetor arrangement herein disclosed. It will be observed that the lower surface 33 of the valve is conical and that the wall 32 leading upwardly from the valve seat is also in the form of a truncated cone, but at a steeper angle than the surface 33 of the valve. As a result of this arrangement suction action upon the air valve is maintained approximately constant regardless of the extent to which the valve is raised from its seat.

The fuel is lifted in the illustrated embodiment from the rear tank 10 to the nozzle 11 by a fuel feed line. My attachment is shown

in the illustrated embodiment as associated with and forming part of this fuel feed line and preferably closely adjacent to the carburetor.

5 The attachment takes the form of a valve and a casing therefor. The casing 40 is closed at its upper end by means of the cap 41 threaded internally therein and is connected to the line 43 to the tank in any preferred or desired manner as for example by the fitting 42 threaded in the casing at one side. The line 44 to the nozzle is illustrated in the drawing as connected to the valve casing 40 at the opposite side by the fitting 45.

15 The casing is provided on its interior with a valve seat 46' to receive the valve 46 thereon. This valve is provided with the upwardly directed stem 47 about which is received the spiral spring 48 having one end 20 in abutting relation to the upper interior wall of the valve closure 41 and having its lower free end seated upon the upper flat surface of the valve. Directed oppositely from the valve 46 is the stem 50 freely received in a narrow channel 51 in the lower half of the valve casing and passing through this channel. The lower end 52 of this stem projects into the enlarged chamber 53 at the lower end of the valve casing.

25 The chamber 53 is still further enlarged to provide the shoulder 57 and the bottom of the casing is closed by the member 55, except for the opening 56, by being threaded therein as shown and between this closure member 55 and the shoulder 57 is received the outer edge 30 of a diaphragm 58 held in position against the shoulder 57 by means of a washer 59.

35 The diaphragm 58 is fixedly secured at its central portion to the lower end of the stem 40 50 in any desired or preferred manner and is made of any resilient or yieldable gasoline resistant material such as cellulose coated silk.

40 The pressure with which the valve 46 is normally maintained on the seat is determined by the pressure applied to the spring 48 and this in turn is controlled by threading the closure member 41 in or out as the case may be. It is understood that the diaphragm 50 shall be of a character that it assumes a position on either side of the normal without being placed under tension and the material 55 specifically mentioned herein is a material of this character. The pressure of the spring 48 should normally be of a character that it 60 will maintain the valve seated until a pressure is attained sufficient to lift gasoline 36 inches, which is generally considered the maximum lift to which a system of this character will be subjected under normal running operations of an automobile. It will be understood, of course, that the exact spring adjustment can be obtained by proper manipulation of the closure 41 with the engine in 65 running operation.

It is contemplated in accordance with my invention that the area of the diaphragm exposed to the action of the fuel head, that is, open to the interior of the casing 40, shall be approximately that of the valve head when seated. Upon viewing the drawing, it will be observed that, in effect, the exposed area of the diaphragm has been made slightly larger than the area of the valve seat and this I have done so as to compensate for the inherent inertia of the diaphragm so that the actual effect of equal heads will be to develop equal pressures.

70 Upon viewing the drawing, it will be observed that the line 44 to the nozzle is open to the valve casing at a point above the valve seat and that the line to the fuel tank 10 is open to the valve casing at a point below the valve seat and intermediately of the valve seat and the diaphragm 58. This is a very important feature of my invention for reasons which will now be pointed out. The valve will necessarily be controlled by and be responsive to the suction conditions in line 44 which is the line to the nozzle. The fuel head on the other hand, whether a negative or a positive one, will act upwardly on the valve head and also downwardly on the diaphragm 58. As the valve head area 75 normally exposed to the fuel head is substantially the same as the diaphragm area open to the same fuel head, the action of the fuel head is in effect resolved into an upward pressure directly on the valve head and an equal downward pressure thereon through 80 the diaphragm 58 and the connecting stem 50 so that, as these two components are substantially equal and in opposite directions, they negative each other and the effect of the fuel head on the valve head is eliminated 85 absolutely as a factor and it can therefore be said that the valve is in no way affected or controlled by the fuel head either whether negative or positive or whether changing 90 from one to the other, or increasing as to 95 one or the other.

100 It will be observed that the diaphragm 58 is open at its lower surface to atmospheric pressure through the opening 56 so as to 105 eliminate any varying factor in the functioning of the diaphragm.

110 One of the essential features of this phase of my invention is that the fuel head is caused to operate to equal degrees and in opposite 115 directions upon the valve and its connected parts and while I have illustrated in the drawing the employment with the valve of a diaphragm, it will be understood that other means than a diaphragm will also be effective 120 for the purposes of my invention. Any such arrangement which will expose to the action of the fuel head an area connected or associated with the valve head and which will be 125 acted upon by the fuel head oppositely to 130

the action of the fuel head upon the valve, will attain the purpose of my invention.

The description thus far given of my attachment has been in connection with a suction feed from a lower level. There may be conditions under which the automobile due to its position on a hill may convert the system into a gravity system. In such an event the head will have become a positive one and will be eliminated by the equal pressure developed on the valve in opposite directions just as has been described in connection with a feed from a lower level tank. It will also be obvious that if the normal feed is a gravity one from a tank at a higher level, the same will be true.

An arrangement or attachment such as herein described can for example be placed in the line between the vacuum tank and the nozzle of the carburetor and the float fuel controlling arrangement eliminated from the carburetor. In fact, my attachment or arrangement can be employed at any point in the system and regardless of the character of the feed at that particular point of the system, its use will render unnecessary any other arrangements heretofore devised for controlling the fuel head and its variations.

Having thus described my invention and illustrated its use, what I claim as new and desire to secure by Letters Patents is—

1. As an attachment to a fuel feed system for automobiles and the like, a valve chamber, a valve seat therein, a valve, means acting automatically to keep said valve on its seat, a diaphragm supported in said chamber in spaced relation to said valve and connected thereto and presenting an area open to the chamber substantially equal to the area of the valve open to the chamber, the valve chamber being open to one side of the valve seat for connection of the conduit to the fuel nozzle and on the opposite side of the valve seat and at a point between the valve seat and the diaphragm for connection to the conduit to the fuel source whereby the action of the head of the fuel from the source of supply upon the valve and the diaphragm and therefore upon the valve will be substantially equal and opposite, thus eliminating this head as a factor in the operation of the fuel feed control.

2. As an attachment to a fuel feed system for automobiles and the like, a valve chamber, a valve seat therein, a valve, means acting automatically to keep said valve on its seat, a member supported in said chamber in spaced relation to said valve and connected thereto and presenting an area open to the chamber substantially equal to the area of the valve open to the chamber, the valve chamber being open to one side of the valve seat for connection of the conduit to the fuel nozzle on the opposite side of the valve seat and at a point between the valve seat and

the member for connection to the conduit to the fuel source whereby the action of the head of the fuel from the source of supply upon the valve and the member and therefore upon the valve will be substantially equal and opposite, thus eliminating this head as a factor in the operation of the fuel feed control. 70

In witness whereof I have signed and sealed this specification this 22 day of July, 75 1929.

CASPAR E. HOFBAUER.
